UNITED STATES PATENT OFFICE.

GEORGE L. GAY, OF PHILADELPHIA, PENNSYLVANIA, ASSIGNOR OF ONE-HALF TO
FRANK WHITTMANN, OF PHILADELPHIA, PENNSYLVANIA.

PORTABLE BAKER'S OVEN.

1,340,946.

Specification of Letters Patent.

Patented May 25, 1920.

Application filed June 5, 1919. Serial No. 302,068.

To all whom it may concern:

Be it known that I, GEORGE L. GAY, a citizen of the United States, residing at Philadelphia, in the county of Philadelphia and State of Pennsylvania, have invented 5 new and useful Improvements in Portable Bakers' Ovens, of which the following is a specification.

My invention relates to a new and useful 10 improvement in bakers' portable ovens, and has for its object to so construct such an oven that cork brick may be used in erecting the same; and

A further object of my invention is to so 15 place the heating pipes in such an oven as to facilitate the heating of the interior of the oven and prevent the banking or stagnation of the air beneath the shelves.

With these ends in view, this invention 20 consists in the details of construction and combination of elements hereinafter set forth and then specifically designated by the claims.

In order that those skilled in the art to 25 which this invention appertains, may understand how to make and use the same, I will describe its construction in detail, referring by numerals to the accompanying drawings forming a part of this application, in 30 which:—

Figure 1, is a vertical longitudinal central section of the oven made in accordance with my improvement; and

Fig. 2, is a section at the line 2—2 of 35 Fig. 1.

In carrying out my invention as here embodied, 1 represents the baking chamber of a portable oven, 2 the heating chamber and 3 the grate bars. The walls of the heating 40 chamber or flue are composed of the fire brick 4 having an asbestos or similar lining 5 and around this asbestos lining are erected the walls of the cork brick 6. The walls which surround the baking chamber 1 are 45 also composed of cork brick and the entire structure is inclosed in sheet metal plates 7 and these plates may have flanges 8 formed therewith by means of which they are secured together by the bolts or screws 9. 50 Thus it will be seen that the furnace may be readily erected and when closed in the metal plates will be rigid and durable and yet when it is desired to pull down the furnace it is only necessary to remove these 55 plates when the cork brick may be removed

one by one for the reerection of the furnace in any other desired location. By constructing a furnace in this manner it will be sufficiently light for erection on upper floors of buildings without the necessity of under 60 pinning on the erection of heavy foundations and may be readily changed from one location to another.

By the use of fire brick in the walls of the heating chamber or flue and backing these 65 fire bricks with asbestos lining the cork bricks are protected against a greater degree of heat so that the furnace will have all the advantages of an ordinary stationary brick furnace with the added advantage of 70 marked decrease in weight and a further advantage of preventing an undue radiation of heat since the asbestos and cork brick serve as insulation.

The baking chamber 1 is divided into a 75 number of compartments by the shelves 10 each of which is composed of an upper and lower tier of pipes 11 having asbestos or similar lining there between and these shelves are set at an angle as clearly shown 80 in Fig. 1, and projecting through the rear wall of the furnace into the heating chamber 2 said pipes being filled with fluid so that when their inner ends are heated this heat will be transmitted to the baking chamber 85 as will be readily understood.

The inclining of the shelves will permit the hot air beneath each shelf to have a forward circulating movement thus preventing 90 the banking or stagnation of this air under the shelves which will greatly facilitate the transmission of the heat from the pipes to the baking chamber.

In practice it will be found that a portable oven constructed in accordance with my invention will carry on the baking process with less consumption of fuel and as it may be erected and operated upon the upper floors of a building better sanitary conditions can be maintained.

Of course I do not wish to be limited to the exact details of construction as herein shown as these may be varied within the limits of the appended claims without departing from the spirit of my invention.

Having thus fully described my invention, what I claim as new and useful is:—

1. A portable oven having a baking chamber therein, the walls of said baking chamber being composed of cork brick, a heating cham-

110

ber the walls of which are composed of fire brick and a lining of asbestos separating the walls of the cork brick from the walls of the fire brick.

5. 2. A portable oven having a baking chamber therein, the walls of said baking chamber being composed of cork brick, a heating chamber the walls of which are composed of fire brick, a lining of asbestos separating the 10 walls of the cork brick from the walls of the fire brick, and sheets of metal inclosing the cork brick.

3. In an oven of the character described, a baking chamber, a heating chamber, pipes leading from the heating chamber to the 15 baking chamber on an incline, cork bricks

surrounding the baking chamber, fire bricks surrounding the heating chamber, and an asbestos lining interposed between the fire brick and the cork brick.

4. In an oven of the character described, a baking chamber, a heating chamber, pipes leading from the heating chamber to the baking chamber on an incline, cork bricks 20 surrounding the baking chamber, fire bricks 25 surrounding the heating chamber, an asbestos lining interposed between the fire brick and the cork brick, and a metal sheaving inclosing the entire structure.

In testimony whereof, I have hereunto affixed my signature.

GEORGE L. GAY.
